DESIGN FOR A BRAIDING

Arnold Garay, New York, N. Y.

Application October 3, 1942, Serial No. 108,422

Term of patent 3½ years

To all whom it may concern:

Be it known that I, Arnold Garay, a citizen of the United States of America, residing in New York city, county of New York, and State of New York, have invented a new, original, and ornamental Design for a Braiding, of which the following is a specification, reference being had to the accompanying drawing, forming part thereof, wherein the figure of the drawing is a plan view of a braiding, showing my new design.

I claim:

The ornamental design for a braiding, substantially as shown.

ARNOLD GARAY.
